UNITED STATES PATENT OFFICE.

CARL W. FINGER, OF WILKES-BARRÉ, PENNSYLVANIA.

REVERSING AND EXPANSION VALVE GEAR.

SPECIFICATION forming part of Letters Patent No. 288,787, dated November 20, 1883.

Application filed August 29, 1883. (No model.)

To all whom it may concern:

Be it known that I, CARL W. FINGER, of Wilkes-Barré, in the county of Luzerne and State of Pennsylvania, have invented a new and useful Improvement in Reversing and Expansion Valve Gears for Steam-Engines, of which the following is a full, clear, and exact description.

Reference is to be had to the accompanying drawings, forming a part of this specification, in which similar letters of reference indicate corresponding parts in all the figures.

Figure 1, Sheet 1, is a plan view, partly in section, of my improvement shown as applied to a locomotive. Fig. 2, Sheet 1, is a rear elevation, partly in section, of a part of the same. Fig. 3, Sheet 1, is a sectional plan view of a part of a cylinder and its steam-port. Fig. 4, Sheet 2, is a sectional side elevation of the improvement shown as applied to a locomotive.

The object of this invention is to avoid the use of eccentrics and link-motions, and economize fuel in working locomotive and stationary steam engines.

A represents the truck-wheels, B the truck-frame, C the boiler-bed, D the boiler, and E the steam-cylinders, of a locomotive. Each cylinder E is provided with a port, F, at each end, which is connected with a live-steam passage, G, and an exhaust-steam passage, H, leading, respectively, to the steam-pipe I and the exhaust-pipe J in the smoke-chamber of the boiler. In each passage G is placed a valve, K, and in each passage H is placed a valve, L, for controlling the movements of live and exhaust steam through the said passages. By this construction each cylinder E is provided with four valves—that is, has a live-steam valve and an exhaust-steam valve at each end. The stems M N of the valves K L pass up through stuffing-boxes O in the top walls of the passages G H. The valves K L are held down to their seats by a constant steam-pressure applied to a small valve, P, placed in valve-boxes Q, attached to or formed upon the brackets R, attached to the top wall of the passage G, or other suitable support, and connected with the steam-ports F. Two collars, S, are secured to each valve-stem M N by set-screws or other suitable means at such a distance apart as to receive between them the end

of a bell-crank lever, T, which is pivoted at its other end to a bracket, R. To the angle of each bell-crank lever T is pivoted a small friction-roller, T', to lessen the friction when the said levers are being operated upon by the cams U V. Two cams, U—one for the forward motion and the other for the backward motion—are provided for each inlet-valve K, and two cams, V, are provided for each exhaust-valve L. The cams U are straight upon their forward edges and tapered upon their rear edges, giving the said rear edges a spiral shape, so that the valves will always be opened at the same point to admit steam, and closed at any desired point of the stroke to cut off steam by moving the said cams laterally upon their shaft W. The cams V are made with their front and rear edges parallel, so as to always open and close the exhaust-valves at the beginning and end of a stroke. All the cams for the valves at each end of the cylinder are placed upon a shaft, W, and are connected with said shaft by tongues and grooves, so that they can be moved laterally upon the said shafts, but will be carried around by and with the said shaft in its revolution. The cams of the two cylinders are separated upon each shaft W by a tubular washer, X or Y, placed upon the middle part of the said shaft. The forward washer, Y, has an annular groove, Z, around its middle part, to receive the end of an elbow-lever, a, or a pin attached to the said end. The lever a is pivoted at its angle to some suitable support connected with the frame of the engine, and to its other end is pivoted the end of a connecting-bar, b, the other end of which is connected with the starting bar or lever in the cab, so that the cams can be readily adjusted upon their shafts to admit and shut off steam to start and stop the engine, to cut off steam at any desired part of the stroke, and to reverse the motion.

Upon the end parts of the shafts W, at the outer ends of the outer cams, U, are placed tubular washers m, around which are formed annular grooves n, to receive the ends of the levers o, or pins attached to the said ends. The levers o are pivoted at their centers to supports attached to the frame of the engine. By this construction the movement of the cams U V upon the rear shaft W will move the

cams U V upon the forward shaft in the opposite direction, so that the cams for giving a forward and a reversed motion must be in diagonal or reversed positions upon the two shafts. The 5 shafts W revolve in bearings connected with the frame of the engine, and to their ends are attached short cranks e, which are connected in pairs at the sides of the engine by rods d, so that the said shafts will always revolve together. To the rear cranks c are also pivoted the ends of connecting-rods e, which pass forward and are pivoted at their other ends to the ends of the short upper arms of the levers f. The levers f are pivoted to a support attached to the frame of the engine, and to their 10 long arms are pivoted the ends of connecting-rods g, the other ends of which are pivoted to the cross-heads h, connected with the piston-rods i of the cylinders E, and also connected by 15 the rods j with the crank-pins k of the drive-wheels l, so that the engine can be controlled and driven without the use of the ordinary link-motion.

Having thus described my invention, I claim
25 as new and desire to secure by Letters Patent—

1. In a valve-gear for steam-engines, the combination, with the cylinders E, of the two inlet-valves K, the two exhaust-valves L, the four bell-crank levers T, the four pairs of cams U V, and the two shafts W, connected 30 with each other by the cranks and rods c d, and connected with the cross-heads of the piston-rods by rods e g and levers f, substantially as herein shown and described, whereby the said cams will be driven to operate the valves 35 from the said cross-heads, as set forth.

2. In a valve-gear for steam-engines, the combination, with the shafts W and the series of cams U V, of the washers X Y m, the equal-armed levers o, and the bent levers a, substantially as herein shown and described, whereby the said cams can be readily adjusted, as set forth.

CARL W. FINGER.
